UNITED STATES PATENT OFFICE.

WILLIAM REID COLLIER, OF AUSTIN, TEXAS.

GUN.

1,318,357.

Specification of Letters Patent. Patented Oct. 14, 1919.

Application filed October 28, 1918. Serial No. 260,027.

To all whom it may concern:

Be it known that I, WILLIAM R. COLLIER, a citizen of the United States, residing at Austin, in the county of Travis and State of Texas, have invented a new and useful Gun, of which the following is a specification.

The device forming the subject matter of this application is a piece of artillery, and the invention aims to provide a structure of the kind mentioned, including a base so constructed that it may be hauled in any direction over the ground, means being provided for weighting the base, and for deflecting the gases from the propelling charge.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:

Figure 1 shows in top plan, a device constructed in accordance with the invention, Fig. 2 is a transverse section of the structure shown in Fig. 1; Fig. 3 is a perspective view showing the towing lug; and Fig. 4 is a fragmental section showing a modification.

In carrying out the invention as disclosed in Figs. 1, 2 and 3, there is provided a cup-shaped base 1 having a lower surface exposed for direct contact with the ground, and convexed as shown at 2 to permit the base to be hauled with equal facility in all directions. Since the outer surface of the base 1 is concaved as shown at 2, the earth may be banked up readily about the base to retain the same. A piece of ordnance upstands from the base 1 and may be of any desired form. As shown in Figs. 1 and 2, the piece of ordnance embodies a boss 13 on the base 1, the boss carrying a pin or projectile-receiving element 4, there being a shoulder 5 at the point where the pin is connected with the boss. A projec-

tile 6 is seated on the pin 4 and carries a propelling charge 7, adapted to be exploded by any suitable firing means 8. A bursting charge 9 may be located in the projectile 6, the bursting charge being retained by a tip 10, and being connected with the propelling charge 7 by means of a time fuse 11. The upper surface of the base 1 is concaved, as shown at 12, and when the projectile 6 is discharged, the gases from the propelling charge 7 will be received in the concavity of the base and be deflected forwardly, away from the operator. The height of the pin 4 will be dictated by the size of the charge 7, but if, as shown in Fig. 2, the pin projects beyond the upper edge of the base 1, the concavity in the base will not be without function as a gas deflecting means, since, even though the charge be exploded at the end of the pin 14 and above the upper edge of the base, some of the gas is certain to shoot backwardly, since there is no laterally operating deflecting means present, saving alone the concavity 12 in the base.

As shown in Fig. 4, the base 14 carries a barrel 15 or projectile-receiving element, Fig. 4 making it clear that the piece of ordnance may be constructed as desired.

Since the base is concaved it is adapted to receive a weight, either for the purpose of anchoring the base to the ground, or for tilting the base if the weight is located properly, so that the projectile may be discharged in any desired direction. The weight may be earth, rock or anything else which is at hand and adapted for the end in view.

The base is provided with undercut lugs 16, disposed in pairs about the base, and located on the inner surface of the base at the upper edge thereof, there being any desired number of pairs of lugs 16. A wedge-shaped block 17 is adapted to be inserted between the lugs 16 of any pair, the block carrying an eye 18 adapted to receive a tow line 19, whereby the base 1 may be dragged readily in any direction over the ground, the convexed outer surface 2 of the base facilitating such an operation.

Generally stated, the device forming the subject matter of this application is simple in construction and well adapted to receive rough usage, it being possible to tow the

structure in any desired direction, and there being no wheels, skids or runners likely to be injured or broken by any force insufficient to work a complete destruction 5 of the device.

Having thus described the invention, what is claimed is:—

1. A device of the class described, comprising a base having a lower surface exposed for direct contact with the ground and convexed to permit the base to be hauled with equal facility in all directions; and a projectile-receiving element upstanding from the base, the upper surface on the 15 base being concaved to receive an anchoring weight.
2. A device of the class described, com-

prising a base having a lower surface exposed for direct contact with the ground and convexed to permit the base to be 20 hauled with equal facility in all directions; a pin on the base; and a projectile seated on the pin and carrying a propelling charge, the upper surface of the base being concaved to form a deflector for the gas from 25 the charge.

In testimony that I claim the foregoing as my own, I have hereto affixed my signature in the presence of two witnesses.

WILLIAM REID COLLIER.
